BRUSH STERILIZER AND DRIER

Carl Schriner, Defiance, Ohio

Application August 13, 1938, Serial No. 224,773

1 Claim. (Cl. 21—90)

This invention appertains to new and useful improvements in means for sterilizing and drying brushes to the extent required by law in some States.

The principal object of the invention is to provide a combination sterilizer and drier which in operation will result in a thorough sterilization of the brush and subsequent drying thereof so that very little time is consumed between customers in treating and drying the brush.

Other important objects of the invention are to provide an apparatus which is of simple construction, of low cost to manufacture and a device which will not be susceptible to the ready development of defects.

These and various other important objects and advantages of the invention will become apparent to the reader of the following specification.

In the drawings—

Figure 1 represents a side elevational view of the apparatus.

Figure 2 is a rear elevational view.

Figure 3 is a fragmentary vertical sectional view taken substantially on the line 3—3 of Figure 1.

Figure 4 is a fragmentary detailed sectional view taken substantially on the line 4—4 of Figure 3.

Figure 5 is a fragmentary detailed sectional view showing the switch.

Figure 6 is a sectional view taken substantially on the line 6—6 of Figure 1.

Figure 7 is a diagrammatic view showing the electrical connections with the switch.

Referring to the drawings wherein like numerals designate like parts, it can be seen that numeral 5 represents the base which has the recess 6 therein for accommodating the lower portion of the sterilizing fluid containing bowl 7. Numeral 8 represents a post rising from one end of the base 5 and provided with the reduced upper end portion 9 which fits into the bifurcated lower end portion 10 of the swingable arm 11. A pin 12 extends through the bifurcated portion 10 and through the reduced portion 9 of the post 8 for swingably connecting the arm 11 to the post 8.

Numeral 13 represents a small electric motor which is secured by the split clamp 14 to the upper end of the arm 11, the clamp being formed with ear portions 15 and a bolt 16 extends through these ear portions for securing the clamp to the arm 11 and in clamped relation with the motor 13.

An elongated centrally bowed stack 17 of 55 as new is:

transparent material is secured to the bottom side of the motor 13 by the split clamp band 18. This stack 17 is of such length as to depend into the bowl 7 and below the surface of the sterilizing fluid therein.

The armature shaft 13a of the motor 13 extends downwardly into the stack 17 and carries the block 19 from which depends a plurality of spring arms 20 each having an inwardly curved end portion 21 which fits under the head portion 22 of the brush 23, which brush can, of course, be especially constructed to accommodate this form of clip or in some instances a clip can be modified to accommodate conventional types of brush handles. From the brush handle 23 of course extends the brush bristles 24.

When the arm 11 is swung downwardly so that the stack 17 depends into the bowl 7, the brush will be immersed in the sterilizing fluid.

Numeral 25 generally refers to the automatic switch which closes the circuit with the battery 26 when the arm 11 is lowered to start the brush rotating in the sterilizing fluid.

As shown in Figure 5, the switch consists of 25 an arm 27 extending laterally from the arm 11 and this is connected by the pivotal link 28 to the contact blade 29 of the switch, which is in wiping engagement with the contact finger 30 stationarily fixed.

30 A case 31 is secured to the post 8 and has an opening 32 in its top side through which the link 29 operates.

Obviously when the arm 11 is swung backwardly the switch is broken and the motor is de-energized. However, when the arm is swung downwardly to the position shown in Figure 1, the motor is operated by the closing of the switch and the brush head operates in the sterilizing fluid, or without the sterilizing fluid, as when the bowl is removed and the operation is to dry the brush.

It is to be understood that artificial means for drying the brush can be employed such as a fan driven by the motor which, of course, will accelerate the drying of the brush and materially reduce the interval of time necessary in accomplishing this result.

50 While the foregoing specification sets forth the invention in specific terms, it is to be understood that numerous changes in the shape, size and materials may be resorted to without departing from the spirit and scope of the invention as claimed hereinafter.

Having described the invention, what is claimed

A sterilizing apparatus of the character described comprising a base having a depression therein, a post rising from the base, an arcuate-shaped arm pivotally secured at one end to the upper end of the post and adapted to abut the post when swung to a position to support a brush over the base, a motor secured to the free end of the arm and including an armature shaft, a spring clip holder for holding a brush in de-

5 pending position, a transparent stack depending from the motor and adapted to depend over the base, a bowl adapted to seat in the depression and to receive the stack when the arm is disposed over the base, said arm being adapted to be swung laterally to permit removal of the brush from the holder.

CARL SCHRINER.
